UNITED STATES PATENT OFFICE.

CLEMENT B. THOMPSON, OF LOS ANGELES, CALIFORNIA, ASSIGNOR OF ONE-HALF TO
WILLIAM A. RUSSELL, OF LOS ANGELES, CALIFORNIA.

WELL SHUT-OFF.

991,392.

Specification of Letters Patent.

Patented May 2, 1911.

Application filed May 3, 1910. Serial No. 559,109.

To all whom it may concern:

Be it known that I, CLEMENT B. THOMPSON, a citizen of the United States, residing at Los Angeles, in the county of Los Angeles and State of California, have invented new and useful Improvements in Well Shut-Offs, of which the following is a specification.

This invention relates to a shut off means adapted to check and direct the flow of fluid 10 from a well when that fluid is flowing with great velocity and under great pressure.

In well drilling, and especially in oil well work, it quite often happens that gas or oil under an enormous pressure is struck. The 15 fluid is projected by this pressure out of the well through the casing at an extremely high velocity, often demolishing the drilling apparatus and in all cases rendering it difficult and dangerous to approach the well in 20 order to shut off the flow. Various methods have been resorted to in order to check the flow, but all methods heretofore used have necessitated the presence of a man in the 25 immediate vicinity for their operation. In some cases the operator has been provided with a diving suit or other apparatus to protect him from the oil and gas.

My device is designed to reduce the velocity of flow so that the fluid may be easily 30 handled without necessitating the presence of any operator within the danger zone. It is kept in position on the casing when it is thought that a body of fluid under pressure is likely to be encountered. In this position 35 it does not interfere at all with the ordinary drilling operation and is ready for instant application at any time.

The device may be closed in many different ways, but I have preferred to show 40 means for closing it by pulling upon cables which run to points outside the danger zone. When once closed the device is held in that 45 position by automatic catches. The fluid is diverted from the head of the casing into a number of discharge pipes or other conveying 50 means of sufficient capacity to easily handle all that can flow through the casing.

In the accompanying drawings: Figure 1 is a vertical section showing my device applied to a well casing. Fig. 2 is a side elevation of the same. Fig. 3 is a sectional plan taken on line 3—3 of Fig. 1.

In the drawings 5 designates the casing of a well to the upper end of which a nipple 55 6 is secured in the usual manner by means

of a collar 7. Nipple 6 is a part of the shut off device and is removed from the casing whenever an extra joint is desired to be put in the hole. Mounted on nipple 6 and in screw threaded engagement therewith is a 60 collar 8 having upwardly and outwardly projecting prongs 9 thereon. These prongs are oppositely disposed and are so placed as to inclose depressions 10 between them and the collar 8.

The main portion of the shut off device is composed of two members 12 and 13, each of these members being of the configuration shown and having hollow interiors for the flow of fluid. Along their central line of 70 juncture each of the members is provided with a downwardly projecting tongue 14, the two tongues forming a wedge shaped partition, or deflecting member, extending downwardly from the tops of the members 75 to a point over the upper end of nipple 6. The lower edge 15 of this wedge shaped deflecting member is comparatively thin and the stream of fluid impinging upon the edge is split into two streams, each flowing 80 around the curve of the interior of one of the members 12 or 13 and thence through outlets 16 into flexible pipes 17 or into any other convenient conveyer. The hollow interiors of members 12 and 13 form chambers 85 into which the fluid flow is deflected by the wedge. The lower edge of one of the tongues 14 is provided with an overhanging ledge 18 which covers the lower edge 90 of the other tongue 14 and thus presents to the upwardly flowing stream of oil a solid surface on the under edge of the deflecting member. This prevents the stream from forcing its way into the joint between the two tongues. To further prevent any pressure from escaping along this joint, member 13 is provided with a lip 19 which overhangs 95 member 12 and forms a tight joint therewith.

Each of members 12 and 13 is provided 100 with a downwardly projecting leg 20 whose lower end rests in one of depressions 10. Ribs 21 strengthen the legs and connect with the body portion of members 12 and 13. At the upper ends of legs 20 the members 12 105 and 13 completely inclose the upper end of nipple 6. A head 25 is provided on the upper end of the nipple, this head having a flange 26 on its upper end. Flange 26 is engaged by a groove in liner 27, the liner being 110

divided into two halves, one half fitting into each of the members 12 and 13. These liners are made in different sizes so that one device may be made to fit all sizes of pipe.

- 5 The members are held together in the position shown by means of catches 30 on their sides; and also by means of cables 31 which are provided with hooks 32, or other connecting means, to handles 33 mounted on the 10 upper portions of members 12 and 13. When catches 30 are released and the tension on the cables is lessened the members will both fall downwardly and outwardly away from each other until ledge 20 rests 15 upon prongs 9. In this position there is sufficient room between the members for the passage of the drilling tools into the casing. This is the position in which the device is normally kept. When a flow of fluid under 20 pressure is encountered and the fluid is ejected with great velocity from the casing it is only necessary that cables 31 be pulled upon from distant points in order to close the device and to divert the flow into pipes 25 17. These pipes may be of any size and number. For ordinary operation a pair of outlets will suffice, but in extraordinary cases it may be necessary to provide either outlets which are larger or to provide two or more 30 for each member. In any case the fluid is easily handled on account of the large capacity of the outlet as compared with the small capacity of the casing. In this manner a large flow of oil may be saved and 35 stored up for future use instead of being allowed to run to waste. The pipes connected with the outlets may be carried to any tank or reservoir as the flow is comparatively slow and the pipe easily handled.
- 40 My invention consists primarily in the combination of a deflector with a chamber into which the escaping fluid is guided so that its upward flow is checked and rendered manageable. More specifically, it consists in 45 certain structural features tending to further the efficiency of the combination, and especially in the combination of a pair or more of chambers and outlets so that the lateral pressures may be equalized.
- 50 Having described my invention, I claim:
1. A well shut off device, comprising in combination with a well casing, a pair of hollow deflecting members having tongues

thereon, the tongues adapted to form together a wedge shaped deflecting wall above 55 the upper end of the casing.

2. A well shut off device, comprising in combination with a well casing, a pair of hollow members pivotally mounted on opposite sides of the casing, each of the members 60 being provided with a downwardly extending tongue, the tongues together adapted to form a downwardly wedge shaped deflector over the upper end of the casing, and outlets for the hollow members, the interior surfaces 65 of the hollow members leading in smooth curves from the wedge shaped deflector to the outlets.

3. A well shut off device, comprising in combination with a well casing, a pair of 70 hollow deflecting members having tongues thereon, the tongues adapted together to form a wedge shaped deflector above the upper end of the casing, and pivotal mounting means for the deflecting members on the 75 casing.

4. A well shut off device, comprising in combination with a well casing, a pair of hollow deflecting members having tongues thereon, the tongues adapted together to 80 form a wedge shaped deflector above the upper end of the casing, pivotal mounting means for the deflecting members on the casing, a collar on the upper end of the casing, and means on the deflecting members for 85 engaging with the collar.

5. A well shut off device, comprising in combination with a well casing, a pair of hollow deflecting members having tongues thereon, the tongues adapted together to 90 form a wedge shaped deflector above the upper end of the casing, pivotal mounting means for the deflecting members on the casing, outlets for the hollow members, the interior surfaces of the hollow members leading 95 in smooth curves from the wedge shaped deflector to the outlet, a collar on the upper end of the casing, and means on the deflecting members for engaging with the collar.

In witness that I claim the foregoing I 100 have hereunto subscribed my name this 23rd day of April 1910.

CLEMENT B. THOMPSON.
